UNITED STATES PATENT OFFICE.

CHARLES E. GOODSPEED, OF SAN DIEGO, CALIFORNIA.

THEFT ALARM FOR AUTOMOBILES.

Application filed May 28, 1924. Serial No. 716,495.

To all whom it may concern:

Be it known that I, CHARLES E. GOODSPEED, a citizen of the United States, residing at San Diego, in the county of San Diego and State of California, have invented new and useful Improvements in Theft Alarms for Automobiles, of which the following is a specification.

My invention relates to theft alarms for 10 automobiles and its principal object is to provide an alarm of this character which will prevent an unauthorized person from driving an automobile without sounding an alarm.

15 A further object is to provide a theft alarm of this character which includes an exhaust gas operated audible signal and a lock controlled mechanism for controlling communication between the signal and the 20 exhaust pipe of an automobile.

Another object of the invention is to provide a device of this character which can be readily installed on any automobile without altering or changing the parts of the 25 same.

With the preceding and other objects and advantages in mind, the invention consists in the novel combination of elements, construction and arrangement of parts and operation, to be hereinafter explicitly referred 30 to, claimed and illustrated in the accompanying drawing, wherein:—

Figure 1 is a view partly in elevation and partly in section of an automobile equipped 35 with my invention.

Figure 2 is a vertical sectional view taken on line 2—2 of Figure 1.

Figure 3 is an enlarged detail view of 40 the device shown partly in elevation and partly in cross section.

Figure 4 is a vertical sectional view of the device, and,

Figure 5 is a similar view taken at right angles to Figure 4.

45 Referring to the drawings in detail, where in corresponding characters of reference denote the corresponding parts throughout the several views, the numeral 5 designates a conventional automobile and 6 the exhaust manifold thereof, having an opening arranged in its upper face at a point below the driver's seat of the automobile. A cylindrical perforated housing or guard is designated at 7 and is formed with a transversely

55 bowed clamp element 8 at its lower end which embraces the upper face of the exhaust pipe 6 as illustrated, and coacts with a similar element 9 embracing the underside of the pipe 6, these clamping elements 8 and 9 being retained in position on the pipe 60 6 by fastenings 10. Arranged centrally within the casing or guard 7 is a whistle 11 having its lower end fast with the clamping element 8 and registering with the opening 7 to permit the exhaust gases to pass from 65 the pipe 6 into the whistle, thence through its outlet 12 to sound the whistle.

In order to control the passage of exhaust gases into the whistle, I provide a valve 13 which is pivoted as at 14 to the lower end 70 of the whistle and when the device is inoperative position, the sound signal occupies a position transversely of the pipe 6 as shown in Figure 4.

Arranged below the driver's seat of the 75 automobile is a conventional key operated lock designated generally at 15 and includes a laterally extending rotatable element 16 which carries an eccentric 17. A crank arm 18 is fixed to the pivot 14 to which the lower 80 end of an operating rod 19 is pivotally connected, the latter passing through the housing or guard 8 and carries a circular stop 20 upon its upper end and which engages the eccentric 17.

85 The operation of the invention is as follows:

The operator rotates the rotatable element 16 by means of a key that he has in his possession which through the instrumentality of the element above mentioned 90 swings the valve to a vertical position to sever communication between the exhaust pipe 6 and the atmosphere.

95 It follows that in the event that an unauthorized person starts the engine of the automobile the exhaust gases passing into the whistle 11 will sound the same and of course indicate to the owner or officers of the law that the automobile is being stolen. 100 When the rotatable element 16 of the lock is rotated in the reverse direction the valve 13 will assume a horizontal position within the lower end of the whistle and permit the exhaust gases to pass through the pipe 6 in 105 the usual manner.

While I have shown and described the preferred embodiment of the invention, it is

to be understood that changes in the arrangement of parts may be made and that I am only limited by the appended claim.

Having thus described the invention, 5 what is claimed is:—

The combination with an exhaust pipe of an automobile, a whistle supported on the exhaust pipe and having communication therewith, a pivoted valve controlling communication between the exhaust pipe and

whistle, a lock including a rotatable element having a laterally projecting stem, an eccentric fixed to the stem, a circular strap engaging the periphery of the eccentric and a rod secured to the circular strap and having operative connection with the pivoted valve.

In testimony whereof I affix my signature.

CHARLES E. GOODSPEED.
